UNITED STATES PATENT OFFICE.

JAMES ROAN, OF PORTSMOUTH, VIRGINIA.

WATER-PURIFYING APPARATUS.

SPECIFICATION forming part of Letters Patent No. 700,826, dated May 27, 1902.

Application filed February 12, 1902. Serial No. 93,783. (No model.)

To all whom it may concern:

Be it known that I, JAMES ROAN, of Portsmouth, in the county of Norfolk and State of Virginia, have invented a new and useful Improvement in Water-Purifying Apparatus, of which the following is a specification.

The apparatus which I have devised while adapted for use wherever it is necessary or desirable to purify water has been designed with more particular reference to its employment in connection with refrigerating and ice-making machinery, and it is in this connection that I shall describe it.

The primary object of the apparatus is to take care of the waste water from the skimmers or skim-tanks and reboiler of an ice-making or refrigerating plant. This water, which is a considerable percentage of what is actually used, under ordinary conditions goes to waste; but by the employment of my apparatus it can be reclaimed, purified, and returned into the general circulation of the system.

I will first describe, in connection with the accompanying drawings, the manner in which my improvements are or may be carried into effect and will then point out more particularly in the claims those features which I believe to be new and of my own invention.

Figure 1 is a side elevation of the apparatus. Fig. 2 is a top view of the same. Fig. 3 is for its left-hand half an end elevation and for its right-hand half a cross-section on line 3 3 of Fig. 1.

A is the tank or body of the apparatus, preferably made as a single casting, and B is the cover therefor, which is tightly bolted to the top of the tank, as indicated. The tank is divided by vertical cross-walls a a into three compartments—the settling-compartment C, the filter-compartment D, and the purified-water compartment E.

F is the water-supply pipe, having two branches F' F², the one entering the settling-compartment, the other discharging into the sewer or other waste-conduit. Each branch is controlled by a cock or valve f' f², by opening the one or the other of which the water can be directed into the apparatus or allowed to run to waste, as the case may be, and there is a third cock f, by which water can be shut off from both branches.

Within the compartment C are a series of vertical baffle-plates c c', extending crosswise of the tank. The bottom plates c are preferably cast in one with the body of the tank. The top plates c' fit in grooves c², cast upon the inner faces of the side walls of the tank and closed at the bottom, so as to form pockets in which the ends of the plates c' fit and are held. By this arrangement the water in its passage through the settling-compartment is compelled to travel in an up-and-down tortuous path, and in so doing deposits much of the solid matter it holds upon the floor of the settling-compartment between the lower baffle-plates c, whence it can be removed through the valve-controlled draw-off pipes c³. Beyond the last baffle-plate c is a valve-controlled gooseneck or dip-pipe c⁴, through which the water is carried off from the settling-compartment and is delivered to the filter-compartment D at a point near the bottom of the latter.

Upon the exterior of one of the walls of the compartment C (in this instance the front wall) and preferably cast in one therewith is an overflow-receptacle O, provided at the bottom with a draw-off pipe o' and at the top or upper end with an overflow-opening o, which is formed in the wall of compartment C and is of such length as to be common to all of the subdivisions of that compartment created by the upper baffle-plates c'. This overflow-opening is located above the normal level of the water passing through the apparatus.

The parts last described can be used as a skimmer to carry off the oil, grease, and other lighter impurities which as they enter the apparatus along with the water may accumulate upon the top of the body of water in the settling-tank. Matters which thus accumulate can be drawn off from time to time by closing the cock on the dip-pipe c⁴ or on the pipe which leads the purified water out from the apparatus. By closing said cock the entering water will be caused to back up in the settling-compartment, thus raising the water-level therein until the overflow-opening o is reached, when the oil, &c., will overflow from the settling-compartment through this opening into the overflow-receptacle O, whence they will pass off through pipe o'.

The bottom of the filter-compartment D ex-

tends below the bottom of the main body of the tank A, as indicated in Figs. 1 and 3, and is provided with a valve-controlled draw-off pipe D'. The cross-partitions *a* form the end 5 walls of this filter-compartment, and on the inner face of these walls are horizontal ledges *a'*, upon which rest the horizontal gratings or perforated diaphragms *d*, which subdivide the filter-compartment and form floors upon 10 which the filtering materials are supported. The water from the settling-compartment enters the filter below the lowermost perforated floor *d* therein. The space between this floor and the one next above is filled with a suitable 15 filtering medium, preferably gravel, and the division next above is packed also with a suitable filtering medium, preferably sponge. Above this is a perforated pressure plate or diaphragm *d'*, which is held down by suitable 20 pressure appliances—as, for example, the spider-yoke *d*—having its outer ends adapted to pass under retaining lugs or ribs *d* on the walls *a* and having at its center a screw-threaded hole for the passage of the pressure-screw *d*, which bears at its lower end upon the holding-plate *d'*. The front of the filter is closed by removable plates *d*, tightly packed and bolted to the body of the tank, thus permitting access to be had to the interior 25 of the filter in order to repack or renew the filtering media or for any other purpose.

The purified water after having passed up through the filtering media is discharged through an opening *d* (just above the top 30 perforated plate *d*) into the end compartment E, whence it is carried off by a valve-controlled gooseneck or dip-pipe *e* back into the circulating system of the refrigerating plant in connection with which this apparatus 35 may be employed or into any suitable storage-tank or other receptacle, according to the use to which it is put.

The compartment E is provided with a valve-controlled draw-off pipe *e* in its bottom and also with a glass gage *e* for indicating the level of the water in the compartment. 40

This apparatus by properly proportioning and regulating the size and capacity of its 45 several parts can be used to take care of the water which enters the reboiler, instead of reclaiming the waste from the reboiler and other parts of an ice plant. Indeed, it is my purpose to duplicate the apparatus—that is to say, to use one such as herein described to receive and take care of the waste water from the reboiler, skimmer, and other portions of a refrigerating plant, and another one of similar construction, but of larger capacity, to 50

preliminarily purify the condense-water supply before it enters the reboiler, for in this way I can prevent the passage to the reboiler of a large percentage of the impurities which under existing conditions it receives. 55

Having described my improvements and the best way of carrying the same into practical effect, I state in conclusion that I do not limit myself narrowly to the structural details hereinbefore set forth in illustration of my invention; but 70

What I claim herein as new, and desire to secure by Letters Patent, is as follows:

1. In a water-purifying apparatus a settling-compartment provided with a valve-controlled outlet and a series of baffle-plates 75 whereby the water is caused to travel the length of the compartment in a tortuous path, and with an overflow-opening which extends practically the length of the compartment and is located above the normal level of the water therein, substantially as and for the purposes hereinbefore set forth. 80

2. A water-purifying apparatus consisting of a settling-compartment, a filter-compartment and a purified-water receptacle or compartment, communicating one with the other in the order named, an inlet-pipe leading the water to be purified into the settling-compartment, an exit-pipe for leading off the purified water from the purified-water receptacle, 85 valves for controlling the flow of water through the several compartments and an overflow-opening formed in and extending practically the length of the settling-compartment at a point above the normal level 95 of the water therein, substantially as and for the purposes hereinbefore set forth. 90

3. A water-purifying apparatus composed of a tank having a removable cover and divided lengthwise by cross-partitions into a settling-compartment, a filter-compartment and a purified-water compartment, communicating with each other in the order named, valves for controlling the flow of water, inlet and exit pipes, removable side plates on the filter-compartment, baffle-plates in the settling-compartment, and an overflow-opening formed in and extending practically the length of the settling-compartment and located above the normal level of the water 100 therein, substantially as and for the purposes hereinbefore set forth. 110

In testimony whereof I have hereunto set my hand this 3d day of February, 1902.

JAMES ROAN.
